UNITED STATES PATENT OFFICE.

CHARLES P. SHEPHERD AND EDWIN S. CONRAD, OF GRAND RAPIDS, MICHIGAN.

SHEET-METAL WORK.

1,016,584.

Specification of Letters Patent.

Patented Feb. 6, 1912.

Application filed January 14, 1911. Serial No. 602,735.

To all whom it may concern:

Be it known that we, CHARLES P. SHEPHERD and EDWIN S. CONRAD, citizens of the United States of America, residing at Grand Rapids, in the county of Kent and State of Michigan, have invented certain new and useful Improvements in Sheet-Metal Work; and we do hereby declare the following to be a full, clear, and exact description of the 10 invention, such as will enable others skilled in the art to which it appertains to make and use the same.

Our invention relates to improvements in sheet metal work, and more particularly to 15 making sheet metal tubes, and its object is to provide improved means for securing the edges to each other at the longitudinal seam of the tube, and it consists essentially of a substantially dovetail recess formed in 20 one edge of the sheet, with a wedge shaped member projecting into the same the recess having a concave bottom portion at each side of the wedge and a bifurcated projection on the opposite edge formed with its 25 outer sides substantially parallel and its ends convex, the respective shape of the recesses and projections being the same, so that when the projections are forced endwise into the 30 said recess and spread apart by the wedge portion the projections completely fill the recesses, thus making a tight joint whereby the edges are locked to each other by a substantially dovetail connection as will more 35 fully appear by reference to the accompanying drawings in which:

Figure 1 represents a portion of a tube embodying our invention; Fig. 2 the same partially formed up; and Fig. 3 the same with the projections partially inserted within 40 the recess.

Like numbers refer to like parts in all of the figures.

1 represents the body of a sheet metal tube having a longitudinal seam as at 2. In one edge of the sheet forming the tube, 45 at convenient intervals, are formed recesses 3 having inwardly diverging opposite walls forming a substantially dovetail recess. At the bottom of each recess is a wedge shaped projection 4 having oppositely inclined 50 sides, whereby there are formed a pair of diverging recesses. On the opposite edge of the sheet forming the tube and opposite each pair of recesses is a bifurcated projection 5 having parallel outer sides and adapted 55 when spread apart by the wedge 4 to fit closely within the recesses 3—3. This spreading action is accomplished whenever the edges of the metal are forced in close contact and the projections forced endwise 60 into the recesses.

What we claim is:—

A sheet metal tube having a longitudinal seam and provided with a recess in one edge having diverging opposite walls, a wedge 65 projecting into the recess, said recess having concave bottom portions at the respective sides of the wedge, and projections on the other edge having convex ends of the same curvature as the concave portions of the recesses and adapted to completely fill the recesses, when forced into the same and spread apart by the wedge. 70

In testimony whereof we affix our signatures in presence of two witnesses.

CHARLES P. SHEPHERD.
EDWIN S. CONRAD.
